ABSTRACT: A device for energizing sequentially and at a given time interval plural loads, such as an electric lamps relays, or a solenoids and deenergizing simultaneously all loads, at a lapse of a certain time after the final load has been energized, does not use any mechanical switching elements. The device comprises an electric circuit consisting of plural stages connected in parallel to a source of electric potential and each including a load and an SCR connected in series. Each stage includes a pair of series-connected variable resistors connected between the cathode of the SCR of one stage and the gate of the SCR of the next succeeding stage, and a condenser connected between the source and the junction point between the pair of series-connected variable resistors.

DEVICE FOR ENERGIZING SEQUENTIALLY PLURAL LOADS

The present invention relates to a device for energizing sequentially plural loads.

An object of the present invention is to provide a device for energizing sequentially and at a given time interval plural loads, such as electric lamps, relays or solenoids, and deenergizing simultaneously all the loads after a lapse of a certain time after the final load has been energized.

Another object of the present invention is to provide a device for energizing sequentially plural loads so constructed that operation, such as mentioned hereinabove, is initiated and suspended automatically according to the intensity of ambient illumination.

BRIEF DESCRIPTION OF THE DRAWING

In the drawing, the single FIGURE is a schematic wiring diagram of a device for energizing sequentially plural loads embodying the invention.

DESCRIPTION OF THE PREFERRED EMBODIMENT

With reference to the single FIGURE of the drawing, the device embodying the invention consists of a load energizing circuit division I, a controlling circuit division II and an illumination reference circuit division III. In order to clarify the operation of the invention, each of these circuit divisions will be described separately.

In the load energizing circuit division I, silicon control rectifier elements SCR_{I-1} , SCR_{I-2} , ..., SCR_{I-n-1} and SCR_{I-n} have their respective anodes connected to one terminal of a source of AC electric potential, and their cathodes are connected to the other terminal of the AC potential source through respective loads L_1 , L_2 , L_3 , ..., L_{n-1} and L_n . Connection between two adjacent silicon control rectifiers, for example SCR_{I-1} and SCR_{I-2} , is such that SCR_{I-1} is connected at its cathode to a gate circuit of SCR_{I-2} through a pair of series-connected variable resistors VR_{Ia-1} and VR_{Ib-1} , and a condenser C_{I-1} , connected to the junction point between variable resistors VR_{Ia-1} and VR_{Ib-1} is connected to such other terminal of the AC potential source. Connections between SCR_{I-2} and SCR_{I-3} , SCR_{I-3} and SCR_{I-n-1} , and SCR_{I-n-1} and SCR_{I-n} are made in the same manner.

In the controlling circuit division II, a diode D_{II-2} is connected at its anode to one terminal of the AC potential source and at its cathode to the other terminal of the AC potential source through a resistor R_{II-1} and a condenser C_{II} . A resistor R_{II-3} is connected at one end to one terminal of the AC potential source and at the other end to the anode of the diode D_{II-1} . Diode D_{II-1} is connected at its cathode to the anode of SCR_{II} , the cathode of which is connected to the other terminal of the AC potential source. A variable resistor VR_{II} has one end thereof connected to a point between the condenser C_{II} and the resistor R_{II-1} , and is connected at its other end to the anode of SCR_{II} . Diodes D_{I-1} , D_{I-2} , ..., D_{I-n-1} have their anodes connected to respective junction points between the pairs of variable resistors VR_{Ia-1} and VR_{Ib-1} , VR_{Ia-2} and VR_{Ib-2} , ..., VR_{Ia-n-1} and VR_{Ib-n-1} and are connected at their respective cathodes to the anode of SCR_{II} . Construction of the controlling circuit division II.

The structure of the illumination reference circuit division III is such that a diode D_{III-1} is connected at its cathode to one terminal of the AC potential source, and at its anode to the other terminal of the potential source through a resistor R_{III} and a condenser C_{III} connected in series. To a point between the resistor R_{III} and the variable resistor VR_{III} , the cathode of a diode D_{III-2} is connected, and the anode thereof is connected to the gate circuit of SCR_{I-1} through a photoconductive element P formed of cadmium sulfide.

The described device operates in a manner which will now be set forth, with the description being divided into two sections, the first section describing the operation of the device without the illumination reference circuit division III and with

the second section describing the operation of the device including this illumination reference circuit division.

In the device without the illumination reference circuit division III when the potential source is closed, the alternating current flows to the gate circuit of SCR_{I-1} through two parallel circuits, one including the resistor R_{II-1} and the diode D_{II-1} , the variable resistor VR_{II} , and resistor R_{II-2} whereby SCR_{I-1} becomes in conductive state for a half cycle, during which a positive potential is applied at the anode of SCR_{I-1} , and current flows through load L_1 . As a result, the condenser C_{I-1} is charged to an ohmic value which approximates the sum of ohmic value of the VR_{Ia-1} , L_2 and that between the gate circuit and the cathode of SCR_{I-2} divided by the sum of the ohmic value of VR_{Ia-1} , VR_{Ib-1} , L_2 and that between the gate circuit and the cathode of SCR_{I-2} . When SCR_{I-1} is turned to a nonconductive state, the charge of the condenser C_{I-1} is discharged nearly to zero through a loop including the condenser C_{I-1} , the variable resistor VR_{Ia-1} and the load L_1 and another loop including the condenser C_{I-1} , the variable resistor VR_{Ib-1} and the gate circuit and the cathode of SCR_{I-2} , and the load L_2 . Each stage of the circuit is given a time constant having a period longer than that of the source of electric potential, so that the DC potential of the condenser C_{I-1} increases at the side near the resistor VR_{Ia-1} . The diode D_{II-1} serves to prevent the condensers C_{I-1} , C_{I-2} , ..., C_{I-n-1} from discharging through the respective diodes D_{I-1} , D_{I-2} , and D_{I-n-1} and the resistor R_{II-3} . When the potential of the condenser C_{I-1} increases, gate current of SCR_{II} flowing through the variable resistor VR_{II} increases sufficiently to trigger SCR_{II} , conductive. SCR_{I-3} , ..., SCR_{I-n-1} and SCR_{I-n} are energized successively in the same manner as SCR_{I-2} . Immediately after SCR_{I-n} becomes conductive, the DC potential of the condenser C_{I-n} is raised sufficiently to supply a gate current to SCR_{II} through the variable resistor VR_{II-n} , thereby energizing SCR_{II} . To SCR_{II} , current from the AC potential source flows through the resistor R_{II-3} and the diode D_{II} . Note that there is provided the circuit including the diode D_{II-2} , the resistor R_{II-1} and the condenser C_{II} , in order to prolong the energizing period of SCR_{II} . That is, the alternating current is converted to direct current by the circuit, and the thus provided direct current flows to SCR_{II} through the variable resistor VR_{II} , after SCR_{II} becomes conductive, whereby a current more than the holding current of SCR_{II} is retained for a certain time period determined by the condenser C_{II} and the variable resistor VR_{II} . As soon as SCR_{II} is energized, current flowing to the gate circuit of SCR_{I-1} through the resistor R_{II-2} is cut off, deenergizing SCR_{I-1} . The respective condensers C_{I-1} , C_{I-2} , ..., C_{I-n-1} discharge through the corresponding diodes D_{I-1} , D_{I-2} and D_{I-n-1} and through SCR_{II} , which results in cutting off the gate current of SCR_{I-2} , SCR_{I-3} , ..., SCR_{I-n-1} and SCR_{I-n} and deenergizing the respective loads L_1 , L_2 , L_3 , ..., L_{n-1} and L_n . When the direct current flowing from the condenser C_{II} decreases below the holding current of SCR_{II} , SCR_{II} is cut off. At this time, the condenser C_{I-n} discharges current through a loop including the variable resistor VR_{II-n} , and gate circuit and the cathode of SCR_{II} , but the current does not flow through SCR_{II} . Thus, the current again flows to the gate circuit of SCR_{I-1} through two parallel circuits, one including the resistor R_{II-1} and the diode D_{II} , another including the resistor VR_{II} , and further through the resistor R_{II-2} , thereby energizing SCR_{I-1} . In the same manner, SCR_{I-2} , SCR_{I-3} , SCR_{I-n-1} and SCR_{I-n} are energized successively, and then deenergized simultaneously. This is repeated as long as the source of AC potential is connected to the circuit.

The device to which the illumination reference circuit division III is combined, operates as follows.

In addition to the circuit as previously described, the diode D_{III-1} is connected at its cathode to one terminal of the source of electric potential and at its anode to the resistor R_{III} . The condenser C_{III} and the variable resistor VR_{III} are interconnected between resistor R_{III} and other terminal of the potential source, thereby providing negative potential at both ends of the variable resistor VR_{III} through the resistor R_{III} . The

diode D_{III-2} is connected at its cathode to a point between the resistor R_{III} and the variable resistor VR_{III} , and at its anode to the gate circuit of SCR_{I-1} through the photoconductive element P, whose resistance increases with decrease of intensity of illumination incident thereupon. The gate potential of SCR_{I-1} is given by the negative potential of the connecting point of the condenser C_{III} with the resistor R_{III} , and the positive potential of the connecting point of the variable resistor VR_{III} with the anode of SCR_{II} divided by the ohmic values of the resistor R_{II-2} and the photoconductive element P. When the resistance of the photoconductive element P decreases, the gate potential of SCR_{I-1} is negative, and SCR_{I-1} is left non-conductive. Accordingly, SCR_{I-2} , SCR_{I-3} , SCR_{I-n-1} and SCR_{I-n} remain in the nonconductive state. When the intensity of illumination incident upon the photoconductive element P decreases and the resistance increases, current flows to the gate circuit and the cathode of SCR_{I-1} to energize SCR_{I-1} . In this connection, the diode D_{III-2} is important to block flow of current to the gate circuit and the cathode of SCR_{I-1} . If the diode D_{III-2} is not incorporated, and when SCR_{I-1} is in conductive state, the potential of the gate circuit of SCR_{I-1} becomes substantially equal to that of other terminal of the potential source. Consequently, the condenser C_{III} is charged with the direct current flowing from the SCR_{II} through the photoconductive element P, and the direct current charged in the condenser C_{III} flows continuously to the gate circuit of SCR_{I-1} through the photoconductive element P. Accordingly, once SCR_{I-1} is energized, SCR_{I-1} is maintained in conductive state, irrespective of energization of SCR_{II} . In order to provide the necessary cutoff of current flow to the gate circuit of SCR_{I-1} , the diode D_{III-2} is connected with a polarity blocking flow of the positive current to the gate circuit of SCR_{I-1} , when SCR_{II} becomes energized. Thus, SCR_{I-1} is cut off, when SCR_{II} becomes conductive.

The invention having the construction as disclosed hereinabove can not only attain the objects disclosed in the preamble, but also provides a device having circuits of a simple structure and operating with no error.

What We claim is:

1. A device for energizing plural loads sequentially comprising, in combination, an electric circuit including plural stages connected in parallel to a source of electric potential, with each stage including a load and an SCR connected in series; each stage including a respective pair of variable resistors interconnected between a cathode of the SCR of the preceding stage and the gate circuit of the SCR of the respective stage; respective condensers, each connected between the source of

electric potential and a respective junction point of a respective pair of variable resistors, whereby said plural loads are energized sequentially at predetermined time intervals; and a further SCR connected in parallel with said condensers to complete a discharge circuit therefor, whereby all said loads are deenergized responsive to conduction of said further SCR.

2. A device for energizing plural loads sequentially comprising, in combination, an electric circuit including plural stages connected in parallel to a source of electrical potential, with each stage including a load and an SCR connected in series; each stage including a respective pair of variable resistors interconnected between a cathode of the SCR of the preceding stage and the gate circuit of the SCR of the respective stage; respective condensers, each connected between the source of electric potential and a respective junction point of a respective pair of variable resistors, whereby said plural loads are energized sequentially at predetermined time intervals, said device further comprising a first series circuit including a first diode, a first resistor and a further condenser, and a second series circuit including a second diode and a further SCR; said first and second series circuits being connected in parallel to the source of electric potential, thereby completing a closed circuit; a further variable resistor connected between the anode of said further SCR and the junction point of said first resistor and said further condenser; respective third diodes each connected in series with a respective one of said first mentioned condensers, the anode of said further SCR being connected to the cathodes of each of said third diodes; and a second resistor connected between the anode of said further SCR and the gate circuit of the SCR of the first stage of said plural circuits; whereby said plural loads are energized sequentially and at a predetermined time interval, and are deenergized simultaneously after all of said loads have been energized.

3. A device for energizing plural loads sequentially, as claimed in claim 2, further comprising a third series circuit including a fourth diode, a third resistor and an additional condenser, and connected in parallel to the potential source; a fourth series circuit including an additional variable resistor, connected in parallel with said additional condenser, a fifth diode and a photoconductive element connected to the gate circuit of the SCR of the first stage of said plural stages; said third and fourth series circuits constituting an illumination reference circuit; said illumination reference circuit automatically initiating and interrupting operation of said device in accordance with the intensity of ambient illumination effective on said photoconductive element.
